UNITED STATES PATENT OFFICE

163,720

AUTOMATIC COUPLING FOR MINING AND
TUNNEL CARSDewey O. Turner, Pine Grove, Calif., assignor, by
decree of distribution, to Dessie Turner

Application January 3, 1950, Serial No. 6,983

Term of patent 14 years

(Cl. D66—1)

To all whom it may concern:

Be it known that I, Dewey O. Turner, a citizen of the United States, residing at Pine Grove, county of Placer, State of California, have invented a new, original, and ornamental Design for an Automatic Coupling for Mining and Tunnel Cars, of which the following is a specification, referring to the accompanying drawing, forming part thereof.

The Figure 1 is a side view of the automatic coupling for mining and tunnel cars; Figure 2 is a top view of the automatic coupling and Figure 3 is an end view of the automatic coupling.

I claim:

The ornamental design for an automatic coupling for mining and tunnel cars, substantially as shown.

DEWEY O. TURNER.
